UNITED STATES PATENT OFFICE.

FREDERICK N. CRANDELL, OF FULSHEAR, TEXAS.

SASH-FASTENER.

1,179,405.

Specification of Letters Patent.

Patented Apr. 18, 1916.

Application filed May 14, 1915. Serial No. 28,050.

To all whom it may concern:

Be it known that I, FREDERICK N. CRANDELL, a citizen of the United States, residing at Fulshear, in the county of Fort Bend and 5 State of Texas, have invented certain new and useful Improvements in Sash-Fasteners; and I do hereby declare the following to be a full, clear, and exact description of the invention, such as will enable others 10 skilled in the art to which it appertains to make and use the same.

This invention relates to fasteners for window sashes; and it consists in the novel construction and combination of the parts 15 hereinafter fully described and claimed.

In the drawings, Figure 1 is a side view of a sash fastener constructed according to this invention. Fig. 2 is a plan view of the same.

20 The upper and lower window sashes 2 and 3, portions of which are shown, are of any approved construction.

A washer plate 4 is secured to the lower sash 3 by means of a screwthreaded eye-bolt 25 5, and a cam-shaped locking plate 6 is pivoted to the eye of the eye-bolt. The eye-bolt has a rectangular eye so that the locking plate cannot tip over sidewise. The outer cam surface of the locking plate 6 is provided with serrations 7 for engaging with the upper sash 2. The inner end portion of 30 the locking plate is substantially concentric with its pivot and it is provided with teeth 8.

35 A stop-dog 10 is hinged to the washer

plate 4 by a pivot pin 12, and is arranged so that it engages automatically with the teeth 8 when the locking plate 6 is in contact with the upper sash. The stop-dog prevents the locking plate from moving upwardly, and it prevents anyone from raising the locking plate from the outside of the window by inserting a knife blade between the window sashes.

When the locking plate is in engagement 45 with the upper sash, as shown, it prevents the upper sash from being lowered and the lower sash from being raised, but it permits them to be slid in the reverse directions.

The locking plate and the stop-dog are 50 both turned over backwardly on their pivots when the device is not required in operation.

What I claim is:

A sash fastener, comprising a washer plate, a single eye-bolt having a rectangular eye and a screwthreaded shank which engages with the upper part of one sash, the washer plate being clamped to the sash by the said eye, a cam plate pivoted on the upper part of the eye and prevented from tipping sidewise by its side portions, said cam plate being adapted to engage with the other sash and having serrations adjacent to its pivot, and a stop-dog hinged to one edge of the washer plate and engaging with the 65 said serrations.

In testimony whereof I have affixed my signature.

FREDERICK N. CRANDELL.
